UNITED STATES PATENT OFFICE

JOHN P. GRUNDON, OF FORT DODGE, IOWA, ASSIGNOR TO SARGENT MACHINE COMPANY,
OF FORT DODGE, IOWA, A CORPORATION OF IOWA

SPRAG ATTACHMENT FOR WHEELED TRUCKS

Application filed November 11, 1929. Serial No. 406,491.

The object of this invention is to provide an improved sprag attachment for wheeled trucks and particularly for trucks which are employed for supporting excavating mechanisms.

A further object of the invention is to provide an improved sprag attachment for wheeled trucks for carrying excavating mechanisms, which attachment is useful, during operation of the excavating mechanism, for relieving a part of the strain on the truck wheels and springs; for keeping the truck wheels from rolling; for stabilizing and preventing the tipping of the truck and devices carried thereby; and for providing a firm base or anchor against which the pull or thrust on the excavating device may be exerted.

More specifically, another object of the invention is to provide an improved sprag attachment for wheeled trucks including a transversely arranged shoe having uprights pivotally attached to the rear end of the truck frame and adapted to support a portion of the load, by being arranged in upright position, when the truck is at rest.

Still another object of the invention is to provide improved means for holding the sprag attachment in inoperative position.

Another and further object is to provide improved means for adjusting the height of the sprag attachment for different trucks or for different conditions of service.

With these and other objects in view my invention consists in the construction, arrangement and combination of the various parts of my device, whereby the objects contemplated are attained, as hereinafter more fully set forth, pointed out in my claims and illustrated in the accompanying drawings, in which:

Figure 1 is a perspective view illustrating a portion of a wheeled truck to which my improved sprag attachment is applied, the attachment being shown in operative position.

Figure 2 is an enlarged side elevation of the same.

Figure 3 is a view similar to Figure 2; the solid lines showing the attachment in inoperative position and the dotted lines illustrating

it in the position assumed immediately prior to placing it in operation.

Figure 4 is a transverse vertical section of the truck and attachment, the right hand side of the section being taken substantially on the line 4—4 and the left hand side being taken on the line 4a—4a of Figure 2.

Figure 5 is an enlarged elevation substantially on the line 5—5 of Figure 4, illustrating the means for lifting the attachment to inoperative position.

For certain kinds of work and particularly for the purpose of facilitating transportation, it is desirable to mount excavating devices on wheeled trucks, such as motor trucks having power plants for moving them from place to place and which may also be employed for operating the excavating device.

In the accompanying drawings I have shown a portion of a rear end of a truck including rear wheels 10 carried by an axle 12 which supports spaced side springs 14 carrying a truck frame 16 which includes spaced I beam sills or side beams.

As here shown, the truck frame supports a platform 18 upon which a boom 20 is pivoted on the horizontal axis 22. The boom 20 may constitute a part of any suitable type of excavating or hoisting mechanism such as a drag line, clamshell, back filler or crane.

It is obvious that by mounting excavating or hoisting devices on a movable truck, the problem of transporting the machine to various places is greatly facilitated. However, this type of mounting is not altogether satisfactory during operation of the mechanism for the reason that the wheeled truck does not afford a stable base or foundation, but is apt to move under stress of the working by rolling of the ground wheels or by tipping of the frame 10 and platform 18 because of being mounted on the truck springs.

My improved sprag attachment is particularly designed for stabilizing the truck frame while the truck is at rest and particularly during operation of the excavating or hoisting device.

I have provided a shoe 24 which may well be composed of a section of heavy wooden plank preferably of a length corresponding

substantially with the width of the truck. The shoe 24 is arranged transversely at the rear of the rear wheels 10 of the truck and is adapted to rest on the ground surface when in operative position.

A pair of posts are spaced apart on and rise from the shoe 24. These posts may be formed of channel beams 26 attached to the upper surface of the shoe 24 by angle braces 28. The channeled posts preferably are arranged immediately behind the two rear wheels of the truck.

A shaft 30 is journaled in the rear portions of the I beams constituting the frame 16 of the truck and the channeled posts 26 are suitably attached to the shaft.

The posts 26 may be attached directly to the ends of the shaft 30, but I prefer to provide means for adjusting the parts at times and for this purpose I have shown arms 32 mounted within the upper ends of the respective posts 26. Each arm is formed with a plurality of spaced apertures 34 to selectively receive a bolt 36 which is extended through one of the posts. Each arm 32 has at its upper end a hub member 38 which receives and is rigidly fixed to the shaft 30. By this means the attachment may be adjusted somewhat as to height, to adapt it for use on different trucks and for different conditions of work.

Each post 26 may carry on its forward face a wooden block 40 which is designed to contact with one of the truck wheels 10 when the sprag attachment is in position for use.

For practical use the attachment is mounted on the truck in such position that when the posts 26 are in vertical position the wooden blocks 40 will engage the rear sides of the truck wheels 10. The parts are also adjusted so that when the attachment is in operative position the weight on the truck wheels and springs will be somewhat relieved and will be borne in part by the sprag attachment. In other words, the distance from the bottom of the shoe 24 to the shaft 30 is slightly greater than the normal height of said shaft above the ground level, so that when the attachment is in position for use, the vehicle springs 14 will be relieved of some of their tension and will not be flattened to their normal extent. This is indicated by the comparative positions of the parts in Figures 2 and 3.

Means is provided for lifting and holding the sprag attachment in inoperative position at times, particularly during traveling of the truck. This means may be of any desired construction, but I have here shown a stub shaft 42 journaled in the rear end of the truck frame 16. The stub shaft 42 carries at one end a hand crank 44 and at the other end a drum 46. A cable 48 is attached at one end to the drum 46 and is adapted to be wound thereon by rotation of the shaft 42 in one direction. The opposite end of the cable 48 is attached to the sprag device as by means of a clip 50 carried by the rear side of one of the posts 26.

The stub shaft 42 is provided with a ratchet wheel 52 and a pawl 54 is pivotally mounted for engagement with said ratchet for holding the shaft and drum 46 against reverse rotation and thereby maintaining the sprag attachment in inoperative position as shown in Figure 3.

When it is desired to use the sprag attachment, the pawl 54 is lifted manually and the device then drops to the position indicated by dotted lines in Figure 3. It will be noted that the device thus assumes an inclined position extending rearwardly and downwardly from the truck frame, with the forward margin of the shoe 24 resting on the ground.

The truck is then backed a short distance, causing the sprag attachment to assume a vertical position and the truck frame rides up onto and is partially supported by the attachment.

It will be noted that the sprag attachment is of sufficient height that it does not entirely assume the weight of the rear end of the truck and that some weight remains on the rear wheels 10 which thus have a tractive contact with the ground surface. It follows that the weight of the truck can be easily and quickly removed from the sprag attachment by simply moving the truck in a forward direction.

When the sprag attachment is in its operative position as shown in Figure 2, it serves as a rigid support to prevent rearward rolling of the truck wheels 10 and that it also prevents lateral tipping of the truck frame and excavating devices by unequal yielding of vehicle springs 14. In other words, the sprag attachment stabilizes the support for the excavating or hoisting mechanism and serves to hold its support in the desired position for operation of the mechanism.

The attachment also serves the function of providing a rigid base or anchor against which pull or thrust of the excavating or hoisting device may be exerted. This function arises particularly in those cases where the boom 20 supports a drag line excavator in which there is a pull of the drag line toward the truck.

This sprag attachment greatly facilitates the operation of excavating and hoisting devices when mounted upon a movable truck.

It is obvious that various changes may be made in the form, sizes, materials and arrangement of the parts, within the scope of the appended claims, without departing from my invention.

I claim as my invention:

1. A sprag attachment for wheeled trucks comprising spaced standards pivoted to the

truck frame, and a shoe carried by the lower ends of said standards, arranged transversely adjacent a pair of ground wheels of the truck, said shoe adapted to contact with the ground surface when said standards are in upright position, for assuming a portion only of the weight of the truck and its load, and buffer blocks carried by said standards for engaging the near-by ground wheels of the truck.

10 2. A sprag attachment for wheeled trucks comprising spaced standards pivoted to the truck frame, ground engaging means on the lower ends of said standards for contacting the ground surface when the standards are in upright position, and buffer blocks carried by said standards for engaging adjacent ground wheels of the truck.

15 Des Moines, Iowa, September 3, 1929.
JOHN P. GRUNDON.
